UNITED STATES PATENT OFFICE.

ISAAC A. BAUM, OF CHICAGO, ILLINOIS.

WINDOW STOOL.

Application filed December 27, 1927. Serial No. 242,631.

My invention relates to buildings and particularly to a form of construction adapted for use in connection with the formation of window sills or stools. It comprises a sheet 5 metal element or combination of elements so arranged as to provide for the reception of a body of cementitious material that is moulded in place and constitutes a window stool. The arrangement is such that the 10 plaster of the adjacent wall may be carried to the edge of the stool and finished at that point without difficulty, a plaster ground being provided for that purpose. In the preferred form, the mould for receiving the cementitious material constituting the window 15 stool is composed of two parts each of which may be independently positioned and applied, thus enabling certain latitude in the previously installed construction elements. 20 The invention will be more readily understood by reference to the accompanying drawing, in which—

Fig. 1 is a sectional view through a window stool and adjacent construction, the 25 parts being arranged in accordance with my invention, and

Fig. 2 is a similar view of a slightly modified form.

In the construction in Fig. 1, the frame 30 or support is indicated at 10, which may be of wood or masonry. A metal window frame is indicated at 11, and a window sash at 12. Metal lath 13 of the usual form may be applied to the wall and plaster 14 35 is laid thereon.

The window stool indicated at 15 is composed of a body of cementitious material moulded in place and confined at its two edges by a pair of mould elements composed 40 of sheet metal and each of angular form in cross section. The rear element is in form of a continuous angle, one leg 16 of which lies flat against the support, and is nailed or otherwise secured thereto. The other leg 45 17 extends vertically and lies alongside of the window frame 11. Its upper margin is rebent as at 18 to provide a key for the cement composing the window stool.

The forward mould element is also of 50 angular form, the leg 19 of which lies

against the support and is nailed thereto, while the leg 20 extends diagonally upward and outward, terminating in a bead 21, having a rebent marginal flange 22 that acts as a key. The bead is so arranged as to provide an undercut recess within which the plaster 14 may enter and which will act as a plaster terminal or key. The face of the bead acts as a plaster ground. 55

While I have shown the mould as composed of two parts, it is obvious it might be constructed in one piece, but without the advantages attendant upon the use of the construction shown. In the form illustrated, the rearward mould element may be mounted flush against the window frame, regardless of the width of the support, with the assurance that the outer mould element may be positioned at exactly the required point in order to insure the proper thickness of 60 65 70 the plaster.

In the construction in Fig. 2, the support 23 and the window frame 24 are similar. Likewise the rear mould element 25 is identical with that illustrated in Fig. 1. 75 However, the forward mould element is somewhat different. It comprises a flat horizontal portion 26 adapted to be nailed to the support, and a terminal portion 27 shaped to constitute a finish or decorative outline for 80 the window stool. The marginal flange 28 is rebent to provide a key for the cement. At an intermediate point, the metal is doubled on itself as at 29 to provide a key for the plaster and a plaster ground, and also 85 to provide a shadow or break between the plaster and the stool, as indicated at 30. This provides a desirable construction where a certain amount of exposed metal is not objectionable. It is in addition somewhat more ornamental than the construction 90 shown in Fig. 1.

Obviously other modifications than those described may be made and I do not wish to be limited except as indicated in the appended claims. 95

I claim:

1. The combination with a support, of a pair of mould elements adapted to be mounted on the support and to provide for a key 100

with the cement constituting a window stool, the outer of said pair of elements being bent to provide a key for plaster and a plaster ground.

5. 2. The combination with a window frame, of a stool mould composed of a pair of sheet metal elements adapted to be independently

positioned, the outer of said elements being bent to provide a key for the cement of the stool and a key and plaster ground for 10 plaster.

In testimony whereof I have affixed my signature.

ISAAC A. BAUM.
